United States Patent Office

Des. 190,900
Patented July 18, 1961

190,900

SLIPPER

Jerome H. Grossman, Bangor, Maine, assignor to Old Town Shoe Company, Boston, Mass., a corporation of Maine

Filed Nov. 18, 1960, Ser. No. 62,892

Term of patent 3½ years

(Cl. D7—7)

FIG. 1

FIGURE 3 is a view similar to FIGURE 1, viewing the same from the opposite position and illustrating particularly the hand lacing of the tongue to the upper of the slipper.

I claim:

The ornamental design for a slipper, as shown and described.
